ELONGATED FLEXIBLE TUBULAR
EXPLOSIVE

Louis F. Porter, Allendale, N. J.

Application April 30, 1946, Serial No. 665,963

2 Claims. (Cl. 102—24)

(Granted under the act of March 3, 1883, as
amended April 30, 1928; 370 O. G. 757)

1

This invention relates to explosive devices, and particularly to improved means for controlling the action and manner of application of the forces generated by the action of explosives. More particularly, the invention is concerned with pre-formed explosives so encased and of such physical shape that the effective forces of their explosion are largely directed in predetermined directions, as a result of which such forces may be most efficiently applied and a minimum of explosive may be employed to accomplish a desired object, with less danger of injury to surrounding objects or personnel, and with less unwanted damage to portions of the target or object worked upon other than the parts whose destruction or the penetration of which may be desired.

The method of directing an explosive blast in a given direction, variously known as the "cavity effect," "shaped-charge effect" or "Munroe effect" has been known and used for many years. Basically, this method requires that the explosive material be provided with a cavity facing in the direction to which the blast is to be directed. Charges employing this principle are commonly constructed in cylindrical form, with a re-entrant cone which is to face the work. In order to achieve the most effective and concentrated blast, such cavity charges must be spaced from the work at the time of detonation, and their efficiency is also greatly increased if the cavity is provided with a liner formed of relatively heavy material, such as a suitable metal; the cavity liner and explosive in combination provide a highly effective cutting agent. The principles involved in the nature and proportioning of the charge, the shape of the cavity, the proportions of the liner, and the stand-off distances required to achieve maximum penetration have been thoroughly investigated and are now well known to persons skilled in this art. An important object of the present invention is to provide improved means for applying the above-outlined principles to charges of elongated or linear construction, whereby an elongated blast is produced especially adapted to the forming of channels, the severing of structural materials, and other work where linear cutting or blasting force is required.

Another object of the invention is to provide an improved linear charge of the character indicated which is readily flexible about relatively short radii and which incorporates within a single smooth casing, which may be of rubber or the like, isolated stand-off or cavity-forming and explosive containing sections, these two sections being separated by a flexible, metallic cavity-defining parti-

tion. Upon explosion, the cavity liner and explosive in combination provide a highly effective cutting agent, in the manner above-outlined. A related object is to provide such a divider which altho of relatively heavy material is readily flexible with the container to permit distortion of the linear charge in the manner above-mentioned while nevertheless retaining the explosive within the upper, charge-containing portion of the casing and preventing escape of any portion of the explosive into the cavity space. Other objects and advantages will be apparent upon consideration of the disclosure in its entirety.

In the drawings:

Fig. 1 is an end view of a mine casing, illustrating in side elevation a length of cavity charge material, constructed in accordance with the present invention, applied to the casing in such manner that the casing is adapted to be completely severed by explosion of the charge;

Fig. 2 is a perspective view on a larger scale of a section of the linear charge material, showing the means whereby end-abutting sections may be joined;

Fig. 3 is a transverse section upon a still larger scale;

Fig. 4 is a longitudinal sectional view taken substantially on line 4—4 of Fig. 3 and looking in the direction of the arrows; and

Fig. 5 is a perspective view of a portion of the flexible liner-divider element.

Referring now to the drawings, reference character 10 designates the hollow tubular container of my improved cavity charge. The container is preferably made of resilient rubber or equivalent material, its cross-sectional contour being best shown in Fig. 3. As indicated in the last-mentioned view, the casing is preferably of rectangular section except for its top, which may be rounded, a flat bottom being provided to lie against the work, and substantially parallel side walls. It will be perceived, however, that the precise contour is subject to variation. One or more pairs of horizontally opposed grooves 12 are provided in the interior surfaces of the side walls, adapted to receive the out-turned flanges 13 of the metallic divider assembly generally designated 15 in Fig. 5. The divider is formed of a metallic channel, the precise shape and angular relationship of the sides of which may be varied to suit the blast characteristics desired. In the illustrative embodiment shown the sides of the divider are disposed at an angle of approximately 80° with relation to one another. Flexibility is imparted to the channel assembly by a plurality

of relatively thin slots 16 extending transversely therethrough at relatively close and regular intervals from the apex to points adjacent the edges of the flanges 13. The extreme edges of the flanges are left integral, however, to tie together the sections formed by the slots. Over the slotted divider is laid a continuous flexible membrane 17 of rubber or the like which serves to seal the slots 16 and prevent the escape of explosive therethrough. If desired, the membrane 17 may form a part of a continuous tubular container for the explosive material 18. The explosive is preferably of putty-like plastic character, and a highly brisant material such as cyclonite.

It will be appreciated that the charges may be made in convenient or standardized lengths, which may be coupled end to end in any desired manner, as by simply taping them together in the manner indicated at 20 in Fig. 2. The ends of the individual sections may be closed by suitable plugs as 22 through which primer detonator assemblies as 24 may project. These may be electrically operable, as indicated, and may also serve to conduct the explosive wave from one section to the next by direct detonation of one another where sections are joined as in Fig. 2.

The sidewalls of the lower portion of the tubular casing serve as stand-off means, to hold the charge and the cavity-defining divider or liner away from the work a proper distance. The sidewalls of the lower portion are preferably thicker than those of the upper portion, as clearly shown in Fig. 3, to prevent collapse of the walls where the charges are used under water, although it will be apparent that reinforcement may be employed as a means for stiffening the walls of the cavity section. The walls may conveniently be made of a rubber material of sufficient stiffness and thickness that the lower portion will withstand external hydrostatic pressure of the order of 40 p. s. i. without greatly impairing its flexibility. The upper section of the tube is, of course, reinforced by the contained explosive and is preferably made thinner, as shown, for compactness and maximum flexibility.

The force of the explosive blast derived from linear cavity charges constructed in accordance with my present invention may be so precisely predetermined that very accurate cutting may be effected without any great danger to nearby structures provided the normal precautions are taken when using explosives. In the typical operation illustrated in Fig. 1, sections of the linear charge have been wrapped around the casing of a mine 25. The wires 21, suitably connected to one of the primers 24, are conducted to suitable energizing and firing means (not shown) for initiating the blast in the well-known manner. It has been found that by the use of charges constructed and arranged in this manner, encased explosives such as the mine 25, when filled with explosive materials of the types ordinarily used, and when not equipped with anti-disturbance devices, may be severed and completely opened

without detonating the explosive charge of the mine or other encased explosive. The present invention may be used to cut or sever explosives or any type derelict completely submerged in water.

While it will be apparent that the preferred embodiment of my invention herein disclosed is well calculated to fulfill the objects first above stated, it will be apparent that the invention is susceptible to variation, modification and change within the spirit and scope of the subjoined claims.

The invention herein described may be manufactured and used by or for the Government of the United States of America for governmental purposes without the payment of any royalties thereon or therefor.

I claim:

1. An elongated flexible tubular container, a flexible partition extending longitudinally therethrough and dividing the same into a lower, cavity and stand-off portion and an upper, explosive containing portion, said partition being contoured to impart a cavity charge effect and being of sectionalized metallic construction and of angular cross-section, out-turned flanges carried by the margins of said partition, the internal walls of said tubular container being provided with slots into which the flanges fit, and a quantity of explosive within said upper portion.

2. An elongated flexible tubular container, a flexible partition extending longitudinally therethrough and dividing the same into a lower, cavity and stand-off portion and an upper, explosive containing portion, said tubular container being of substantially rectangular cross-section and provided with a plurality of pairs of horizontally disposed internally opening slots in its inner walls, said partition being contoured to impart a cavity charge effect and arranged to occupy any one of said pairs of opposed slots whereby the vertical positioning of the partition may be varied, and a quantity of explosive within said upper portion.

LOUIS F. PORTER.
